UNITED STATES PATENT OFFICE.

RUSSELL M. SEWARD, OF COLUMBUS, OHIO.

CURTAIN-PIN.

SPECIFICATION forming part of Letters Patent No. 774,993, dated November 15, 1904.

Application filed February 13, 1904. Serial No. 193,391. (No model.)

To all whom it may concern:

Be it known that I, RUSSELL M. SEWARD, a citizen of the United States, residing at Columbus, in the county of Franklin and State 5 of Ohio, have invented a certain new and useful Improvement in Curtain-Pins, of which the following is a specification.

My invention relates to curtain-pins of that class which are adapted for use in pinning the 10 borders of lace curtains to carpets for the purpose of stretching and drying the same.

The objects of my invention are to provide an improved pin of this character of superior construction, to provide an improved construction of curtain-pin whereby a plurality of lace curtains may be held in properly-stretched conditions by the same pin, and to produce other improvements in details of construction, which will be more fully pointed 20 out hereinafter.

These objects I accomplish in the manner illustrated in the accompanying drawings, in which—

Figure 1 is a view in perspective of my improved pin. Fig. 2 is a side elevation of the 25 same; and Fig. 3 is a sectional view through portions of a carpet and two curtains, showing the manner of utilizing my invention.

Similar numerals refer to similar parts 30 throughout the several views.

In carrying out my invention I form my improved pin of a single piece of wire 1, the latter being bent at a suitable distance from one of its ends to form an upright or vertical 35 loop 2, the terminal portion of this loop 2 being again bent to form a rearwardly-extending and substantially horizontal loop 3 at the base of the loop 2. The terminal portion of the loop 3 is continued from said loop forwardly and 40 coiled, as indicated at 4, a desirable number of times about the rear or inner portion of the forwardly-extending pin member 5 in front of the loop 2. The coil 4 terminates in an upwardly-projecting or vertical pin member 6, and the pin member 5, which forms the other 45 terminal of the wire, is preferably curved slightly upward and provided with a pointed termination, as shown.

In utilizing the pin formed as above described the loop 3 is intended to be grasped 50

between the thumb and forefinger of the hand, with the thumb uppermost and abutting against the loop 2. In order to pin a lace curtain or other article, such as is indicated at 7, to a carpet, as 8, the forwardly-extending and curved pin member 5 is passed through the open-work of the curtain-border and thence into the carpet in the usual manner. It being desired, however, to employ the pin for engagement with an additional curtain, such as is indicated at 9, the open-work border of the latter is engaged by the upwardly-projecting pin member 6, thus providing for the pinning of more than one curtain to a carpet or other floor-covering in such manner as 65 to bring the curtains held thereby one above the other, thereby overcoming the necessity of employing a separate set of pins for each curtain to be stretched and dried.

It will be observed that by the construction 70 described my improved pin is formed of but one piece of wire and that the same is so bent or looped as to not only provide means for readily and easily grasping and inserting the same, but to form a double pin-body of de- 75 sirable rigidity.

Having now fully described my invention, what I claim, and desire to secure by Letters Patent, is—

1. In a curtain-pin, an extended carpet-engaging prong, an upright loop supported from the prong, a horizontal loop extending rearwardly from the upright loop, and a curtain-engaging pin supported by the prong in juxtaposition to the upright loop. 85

2. A curtain-pin comprising a single piece of wire having a pointed pin-terminal portion 5, said wire being bent at the inner termination of said pin portion 5 to form an upright loop 2, the latter being continued to form a 90 horizontal loop at the base of the loop 2 and said horizontal loop portion being continued forward, wound about the rear portion of the pin 5 in front of the loop 2 and thence projected upward to form a substantially vertical 95 pin 6, substantially as specified.

RUSSELL M. SEWARD.

In presence of—

C. C. SHEPHERD,
W. L. MORROW.
